UNITED STATES PATENT OFFICE.

GEORGE R. LONG, OF WATERBURY, CONNECTICUT, ASSIGNOR, BY MESNE ASSIGNMENTS, TO CORDLEY AND HAYES, OF NEW YORK, N. Y., A CORPORATION OF NEW YORK.

FAUCET.

1,238,926.

Specification of Letters Patent.

Patented Sept. 4, 1917.

Application filed October 4, 1915. Serial No. 54,059.

To all whom it may concern:

Be it known that I, GEORGE R. LONG, a citizen of the United States, residing at Waterbury, in the county of New Haven, State 5 of Connecticut, have invented certain new and useful Improvements in Faucets, of which the following is a description, reference being had to the accompanying drawings, forming a part hereof.

10 My invention relates to faucets particularly to faucets of the push button type adapted for use with water coolers and other liquid dispensing devices and is an improvement on the faucets forming the subject-matter of Letters Patent No. 953,342, dated March 29, 1910 and No. 987,633, dated March 21, 1911.

15 The object of the invention is to provide a simple and relatively inexpensive faucet, the body or shell of which may be made in one piece of seamless tubing with the valve seat formed integrally with the body portion, in which the valve and valve rod will be simple in construction and easily assembled, and 20 25 in which danger of leakage past the discharge opening will be effectively guarded against.

With these and other objects herein described in view, my invention consists in the 30 construction and combination of elements hereinafter set forth.

Referring to the drawings,

Figure 1 is a longitudinal sectional view of a faucet embodying my invention.

35 Fig. 2 is an end view of the inner end of the faucet.

Fig. 3 is a longitudinal sectional view of the valve and valve rod.

Fig. 4 is an end view of the spring clip 40 on the outer end of the valve rod.

Fig. 5 is a perspective view of the cup which forms the abutment for the inner end of the valve closing spring.

45 Fig. 6 is a perspective view of the spring clip shown in Fig. 4.

Fig. 7 is a perspective view of the outer end of the valve rod.

In the drawings, 1 is the socket portion of 50 the faucet body and 2 is the main portion. The socket portion and main portion are both cylindrical in cross section and the socket portion 1 is of relatively large diameter and the main portion 2 is of relatively

small diameter. At its free end, that is, at the end away from the main portion 2, the 55 socket portion is provided with a flange which extends outward at 3 and then in a direction parallel with the axis of the faucet body at 4, this portion 4 of the flange being non-circular in cross section, in the faucet 60 illustrated being hexagonal, as shown in Fig. 2, to permit of being grasped by a wrench to screw the faucet onto the end of the pipe to which it is to be applied, the socket portion 1 being interiorly screw- 65 threaded at 5.

Between the cylindrical socket portion 1 and the main portion 2 of the socket body is formed an inwardly projecting shoulder 6, this shoulder extending inward to a diameter substantially less than the interior diameter of the main portion 2. At a point toward the outer end of the main portion 2 but some distance from this end, is formed an inwardly extending shoulder 7 which, 70 however, has an interior diameter only slightly less than the interior diameter of the main portion 2. The faucet body between the cylindrical socket portion 1 and the shoulder 6 is tapered, as shown at 8. 75 Near the shoulder 7 on the outside of the main portion 2 is secured a ring 9 preferably having a thin flange 10 at its base which is spun or forced into the depression on the outside of the main portion opposite 80 the shoulder 7.

Between the shoulders 6 and 7 is formed a discharge opening 11 and a spout 12 is preferably secured to the main portion 2 of the faucet body by a flange 13 surrounding 90 the opening 11.

Within the tapered portion 8 is arranged the valve 14 adapted to rest against the shoulder 6 and carried on the end of valve rod 15. This valve rod has formed on it, 95 by upsetting or otherwise, near its inner end a ring 16 of less diameter than the interior diameter of the shoulder 6 and is centrally bored out at its inner end, as shown at 17. Resting against the ring 16 100 between it and the inner end of the valve rod is a disk of non-metallic material 18 such as soft rubber or leather adapted to form a tight closure with the valve seat formed by the shoulder 6. Between the disk 105 18 and the inner end of the valve rod is a

metallic disk or washer 19 having its outer diameter substantially the same as the inner diameter of the shoulder 6. The inner end of the valve rod is turned outward, as shown 5 at 20, against the metallic disk or washer 19 to hold it and the disk 18 between it and the ring 16.

The valve rod extends through and is guided in the bottom of a cup 21, the inner 10 end portion of which is reduced in diameter so as to extend through and fit snugly in the interior of the shoulder 7, the portion of the cup outside the shoulder 7 being of larger diameter to fit the interior of the 15 main portion of the faucet body, a shoulder being formed in the sides of the cup between the inner reduced portion and the outer portion which fits against and makes a tight joint with the shoulder 7 and also prevents 20 the reduced portion from extending too far toward the spout 12.

The valve rod is forced outward to hold the valve 14 against the valve seat formed by the shoulder 6 by the means shown and 25 described in Letters Patent No. 987,633, dated March 21, 1911, above referred to, this means comprising a spring 25 bearing at one end against a washer 26 within the cup 21 and separated from the bottom of the 30 cup by a disk 27 of non-metallic material such as soft rubber or leather, and bearing at its outer end against a spring clip 28, as shown in Figs. 4 and 6, which is adapted to engage notches 29 on the outer end of the 35 valve rod 15, this spring clip having an outwardly projecting lug 30 which engages an opening 31 in a push button 32, the inner end of which fits and slides within the outer end of the main portion 2 of the 40 faucet body.

The faucet body is formed of seamless tubing which may be of relatively slight thickness, the flange 3, 4 giving strength to the socket portion 1 which needs to be of 45 material only thick enough to carry the screw-threads 5, the hexagonal or other non-circular form given to the portion 4 of this flange adding to the strength of the socket portion.

Having thus described my invention, what I claim is:—

1. A faucet body formed of one piece of tubing of substantially the same thickness throughout having at one end a socket integral therewith of relatively large diameter, a main portion of relatively small diameter and an inwardly bent shoulder integral with the body between the socket and the main portion adapted to form a valve 55 seat.

2. A faucet body formed of one piece of tubing of substantially the same thickness throughout having at one end a socket integral therewith of relatively large diameter 65 with a noncircular flange on its free end,

a main portion of relatively small diameter and an inwardly bent shoulder integral with the body between the socket and the main portion adapted to form a valve seat.

3. A faucet body formed of one piece of 70 tubing of substantially the same thickness throughout having at one end a socket integral therewith of relatively large diameter, a main portion of relatively small diameter and an inwardly bent shoulder integral with the body between the socket and the main portion adapted to form a valve seat and a second inwardly bent shoulder 75 integral with the body near the outer end of the main portion.

4. A faucet body formed of one piece of tubing of substantially the same thickness throughout having at one end a socket integral therewith of relatively large diameter with a noncircular flange on its free end, a 80 main portion of relatively small diameter and an inwardly bent shoulder integral with the body between the socket and the main portion adapted to form a valve seat, and a second inwardly bent shoulder integral with the body near the outer end of the main 85 portion.

5. A faucet body formed of one piece of tubing of substantially the same thickness throughout having at one end a socket integral therewith of relatively large diameter with a noncircular flange on its free end, a 90 main portion of relatively small diameter and an inwardly bent shoulder integral with the body between the socket and the main portion adapted to form a valve seat, and a second inwardly bent shoulder integral with the body near the outer end of the main 95 portion.

6. A faucet body formed of one piece of tubing of substantially the same thickness throughout having at one end a socket integral therewith of relatively large diameter, a main portion of relatively small diameter and an inwardly bent shoulder integral with the body between the socket and the main portion adapted to form a valve seat, in combination with a valve adapted 100 to seat against said shoulder, and a valve rod having a ring near its end and having its end bored out and outwardly turned to hold the valve between it and the ring.

7. A faucet body formed of one piece of tubing of substantially the same thickness throughout having at one end a socket integral therewith of relatively large diameter with a noncircular flange on its free 115 end, a main portion of relatively small diameter and an inwardly bent shoulder integral with the body between the socket and the main portion adapted to form a valve seat, and a second inwardly bent shoulder 120 integral with the body near the outer end of the main portion.

125

integral with the body near the outer end of the main portion, a cup having its end reduced in diameter and extending through said second shoulder and having a shoulder 5 therein resting against said second shoulder, and a valve rod extending through said cup having a ring near its end and having its end bored out and outwardly turned to hold the valve between it and the ring, the

bottom of the cup serving as a guide for the 10 valve rod.

This specification signed and witnessed this 28th day of September A. D. 1915.

GEORGE R. LONG.
